TRAVELING BLOCK

Glenn D. Johnson, Compton, Calif.

Application August 20, 1945, Serial No. 611,517

3 Claims. (Cl. 254—194)

1

The present invention relates to oil tools and particularly to a traveling block.

An object of the invention is the provision of a block incorporating novel structural features, wherein the parts are so arranged that external projections are eliminated. The average block now known to the inventor is not streamlined, but has numerous projections extending from the outer surface thereof. Such projections may endanger workmen or interfere with the proper operation of the block.

An object of the invention is to provide a novel means in a traveling block whereby the lines may be readily reeved without the necessity of disassembling the block.

Another object is the provision of a traveling block which permits ready access to the interior of the block for any purpose desired, such as inspection of the parts, minor repairs, and the like.

A further object of the invention is to so relate and connect the block, guard and clevis that it is unnecessary to disassemble the unit in order to reeve the block by looping the lines or to attach hooks, elevators or other tools to the clevis.

A further object is to provide a traveling block which is economical in cost of manufacture and generally superior to blocks now known to the inventor.

With the above mentioned and other objects in view, the invention consists in the novel and useful provision, formation, construction, association and relative arrangements of parts, members and features, all as shown in a certain embodiment in the accompanying drawings, described generally and more particularly pointed out in the claims.

In the drawings:

Fig. 1 is a perspective view of the traveling block;

Fig. 2 is a perspective view of the block shown in Fig. 1, certain parts of the block being moved to a new position;

Fig. 3 is a transverse section of the block showing the interior construction;

Fig. 4 is a sectional view on the line 4—4 of Fig. 3;

Fig. 5 is a fragmentary end elevation of the block, certain of the elements thereof being swung to an open position; and,

Fig. 6 is a front elevation of the block looking in the direction of the arrow 6 of Fig. 5.

Referring now to the drawings:

The block is designated as an entirety and in

one embodiment by the numeral 1, and the same includes a plurality of sheaves 2 mounted in any convenient manner, such as by providing a center pin 3 and intermediate bearings 4. The center pin 3 is held within a casing which encloses the sheaves in any convenient manner, as illustrated at 5. Details of this construction are not set forth here and form no part of the present invention. The casing which surrounds the sheaves must of necessity be strong enough to provide adequate support for such tools as are lifted by the said block.

The casing includes side sheave plates 6 and 7, which may be cast integrally with or separable from a side guard. This side guard 8 encompasses the upper portion of the casing and is formed with transverse steps or shoulders 9 and 10. In the present embodiment the guard portion 8 is fixed to the side sheave plates, while guards 11 and 12 form continuations of the guard 8 and are separable therefrom. The guards 11 and 12 are shown as having a progressively varying transverse sectional width, although such a structure need not of necessity be resorted to, in that the said portions may be of uniform section. The side sheave plates 6 and 7 are provided with a spaced pair of knuckles 13 and 14, and attached so as to swing relative to one or the other of said knuckles are the guards 11 and 12 and a clevis 15. Both guards are provided with aligned pairs of transverse bores, as shown for one pair in Fig. 4 at 16, 17. The end walls 20 and 21 are equally spaced from the knuckle members 13 and 14. The clevis is provided with two spaced pairs of knuckles 22, 23, 24 and 25, adapted to be received in space included between the knuckles 13 and 14 and the end walls 20 and 21 of the guards 11 and 12. When the guards 11 and 12 and the clevis 15 are all cooperating and in closed position, as for instance illustrated in Figs. 1, 3 and 4, pins 26 and 27 are passed through the aligned openings of the guards and knuckle members and secured in any approved manner, such as by means of nuts. To hold the guards 11 and 12 in proper working relationship and independent of the pins 26 or 27, I have provided a stabilizing bar 28, which bar is integrally associated with the said guards at 29 and 30, see Fig. 6.

The guards 11 and 12 are stepped or shouldered transversely at 31 and 32, so as to cooperate with the stepped portions 9 and 10, see Fig. 4. The casing is provided with an opening at 33, which may accommodate a hook, the said opening being on the diametric center of the casing, to

the end that weight hung from the clevis is distributed evenly over the entire block. It is of course realized that sheave plates are usually interposed between the various sheaves, which sheave plates, along with the casing, carry the load.

The guards 7 and 8 are provided with spaced slots 34 and 35 which lie in the plane of the grooves of the sheaves. These slots are segmental and are enlarged at 36 for passage of rope or wire line therethrough.

The operation, uses and advantages of the invention just described are as follows: By interconnecting the guards 11 and 12, clevis 15 and main body of the block through the medium of pins 26 and 27, it is possible by the removal of one of said pins to allow the clevis to swing to an open position, as illustrated in Fig. 5, and likewise to allow the guard members 11 and 12 to move to the position shown in Figs. 2, 5 and 6 to permit a ready threading of a line over the sheaves without disassembling the block as is necessary in ordinary constructions. The workman is permitted direct access to the sheaves without interference. It is a simple matter to swing the guards 11 and 12 from the position of Fig. 2 to that of Fig. 1, as well as to move the clevis and permit the pin 27 to be reinserted through the knuckles and secured. It is quite impossible for a wire line or rope to jump the sheave grooves in a construction of the type described, because the guards, both fixed and movable, closely confine the sheaves by being adjacent the peripheries of the sheaves.

The traveling block has a pleasing appearance due to the smooth exterior of the casing, which smoothness assures that there will be no hanging of the block when it happens to strike or engage projecting objects.

The actual threading of the line through the block is not detailed, because such threading is well understood in the art.

I claim:

1. In a traveling block, a casing having a pair of spaced apart side sheave plates, sheaves mounted for rotation between said side sheave plates, a fixed guard for the upper half of said casing, secured between said side sheave plates, said fixed guard provided with slots lying in the plane of said sheaves, a movable guard, a pin for swingingly mounting the movable guard to the lower portion of the casing and forming a smooth surfaced continuation of the fixed guard, and a clevis carried by said pin.

2. A traveling block, the external surface of which is substantially free of all obstruction, including a casing having a pair of spaced apart side sheave plates, sheaves mounted for rotation between said side sheave plates, a fixed guard extending between said side sheave plates and enclosing the upper diametric half of said sheaves, a knuckle depending from each side sheave plate, a clevis formed with two spaced pairs of knuckles between which are positioned the knuckles of the side sheave plates; a pair of guards encasing the lower diametric half of said sheaves and the outermost sides of the clevis knuckles and forming a smooth surfaced continuation of the fixed guard; and means passed through the knuckles, and last named pair of guards for maintaining the same in working relationship.

3. In a traveling block, a casing the external surface of which is substantially free of all obstruction, said casing having a pair of spaced apart side sheave plates between which sheaves are mounted for rotation, fixed guards forming a continuation of the side sheave plates, and enclosing the upper diametric half of said sheaves, a pair of movable guards enclosing the lower diametric half of said sheaves and forming a smooth surfaced continuation of the fixed guard, a knuckle depending from each side sheave plate, a clevis provided with a spaced pair of knuckles between which are positioned the knuckles of the side sheave plates; a stabilizing bar secured between said movable guards, said movable guards being enlarged in the zone of the knuckles to overlie the sides of said knuckles, and bolts passed between the movable guards and through the knuckles for securing the same in working relationship, and whereby removal of one of said bolts permits the clevis to be swung downwardly for access thereto, and likewise permits the movable guards to be separated from the casing to permit access to the sheaves.
